UNITED STATES PATENT OFFICE.

ANTON WILD, OF SAGINAW, MICHIGAN, ASSIGNOR TO WERNER & PFLEIDERER CO., OF SAGINAW, MICHIGAN, A FIRM.

MACHINE FOR FOLDING NOODLES.

1,108,294.

Specification of Letters Patent. Patented Aug. 25, 1914.

Application filed April 15, 1913. Serial No. 761,242.

To all whom it may concern:

Be it known that I, ANTON WILD, a subject of the Emperor of Germany, residing in Saginaw, in the county of Saginaw and State of Michigan, have invented certain new and useful Improvements in Machines for Folding Noodles, of which the following is a specification.

This invention relates to machines of the kind employed for folding strips or ribbons of dough into loaves or bunches, and particularly to that class of such machines as are adapted to fold noodles. In such machines it is usual to wind a sheet of dough on a horizontal shaft or arbor from which it is led between feed-rolls which advance the sheet and reduce it to the desired thickness and which deliver the sheet thus prepared to cutters which divide it into strips or ribbons which latter are subsequently cut into proper lengths to form noodles.

According to my invention I produce strips of dough or noodles in the way just described and I then fold them in a novel way by novel mechanism which receives the noodles from the cutters, folds them, and delivers them in a folded condition to a carrier which conveys them away from the folding mechanism.

The machine embodying my improvements involves no substantial change in the cutting mechanism but novel folding mechanism is adapted to receive the noodles after they are severed into proper lengths, cause them to assume diagonal positions relatively to the line of movement of the folder and then fold them by first turning the end portions over upon the middle portions of the noodles and then folding along the middle line of the noodles to produce completely folded noodles having four thicknesses of dough.

The folding mechanism comprises a series of sets of folding tables connected with sprocket chains which are operated to carry the tables successively beneath the cutting mechanism. Each set in the preferred form of machine comprises four tables, the combined length of which equals approximately the length of the noodles. The noodles are delivered to a set of tables so that their opposite ends register approximately with the outer edges of the two end tables and then as the tables are moved forward they are shifted laterally to cause the noodles to be

arranged diagonally and then two of the tables are turned automatically in such manner as to turn the two end portions of the noodles over upon the middle portion thereof and as the tables further advance another one of the tables is operated to turn one of the folded or doubled portions of the noodles over upon the other folded or doubled portion. This completes the folding operation and as the tables advance the folded noodles are delivered to an endless carrier which conveys them away. The tables are automatically returned to normal position before receiving more noodles from the cutters.

My improvements are illustrated in the accompanying drawings, in which,

Figure 1 shows a side elevation of a noodle cutting and folding machine with my improvements applied. Fig. 2 shows a vertical section of the upper part of the machine where the cutters are located. Fig. 3 shows a horizontal section approximately on the line 3—3 of Fig. 1 but with the tables removed. The remaining figures of the drawings are on an enlarged scale. Fig. 4 shows a vertical section on the line 4—4 of Fig. 5. Fig. 5 is a detail view showing particularly the gearing connecting one of the knife shafts with a shaft of the endless conveyor chains for the tables. Fig. 6 is a detail view in longitudinal section showing the tables and their supporting and operating mechanism. Fig. 7 shows a transverse section of the same mechanism. Fig. 8 is a top plan view of the tables with their operating mechanism in section and some parts shown by dotted lines. Figs. 9 to 16 inclusive show details of the four tables of a set with some of their associated parts. Figs. 9 and 10 show the table of a set which is operated to make the first fold at the front ends of the noodles. Fig. 11 shows a section on the line 11—11 of Fig. 10. Fig. 12 shows a section on the line 12—12 of Fig. 10. Fig. 13 shows a second table of the set and some of its associated parts. This table is not turned but supports and delivers the completely folded noodle. Fig. 14 shows parts of the third table in the set and some of the associated parts, which table is operated to make the final fold in the noodle. Fig. 15 shows portions of the fourth table in the set and some of its associated parts, this table being operated si-

multaneously with the first table to give the first fold at the rear ends of the noodles. Fig. 16 is a detail view partly in plan and partly in section showing how the tables are connected with the conveyer chains and how the tables are connected with each other. Figs. 17 to 20 inclusive illustrate diagrammatically how the mechanism is operated step by step to fold the noodles. Fig. 17 shows the four tables in a horizontal position and supporting a series of noodles on them. Fig. 18 shows how the first and fourth table are operated to make the first folds at the opposite ends of the noodles. Fig. 19 shows how the first and fourth tables are returned to their horizontal position and the third table is operated to give the second fold to the noodles and deposit them on the second table which conveys them to the carrier that delivers them to their destination. Fig. 20 shows the condition of the tables after the third table in the series has been returned to its normal horizontal position. Fig. 21 shows how the sheet of dough after having been divided into ribbons and cut to proper length are deposited in a parallel condition on a set of four tables. Fig. 22 shows how the tables are shifted laterally in opposite directions to cause the noodles to assume a position diagonal to the line of movement of the conveyer chains. Fig. 23 shows how the noodles after having been arranged diagonally are folded at opposite ends. Fig. 24 shows how one of the folded ends of the series of noodles is folded over upon the other folded portion thereof. Fig. 25 is a perspective view showing a portion of a completely folded noodle.

A sheet of dough A is wound upon an arbor *a* and led through rollers B which press it to the desired thickness and advance it to rotary cutters C which cut the dough sheet into strips or ribbons of suitable width. The dough strips descend across the edge of a guide board D which is adjustable to vary the position of its lower front edge *d*. This adjustment may be obtained in various ways. It will be observed, however, that in the construction shown the guide board is pivotally connected with the frame of the machine at *d'* and it is jointed at *d''* to an arm D' which extends through a horizontally arranged shaft *d''*. By means of adjusting nuts *d''* the length of this arm may be varied to thus vary the position of the edge *d*.

E indicates a rotating knife which is operated to sever the strips or ribbons of dough into suitable lengths.

The mechanism above described is for the most part of well known construction.

The frame F of the machine may be of any suitable construction for supporting the cutting mechanism and it is provided with an

extension F' supported by braces or standards F''. Within this extension of the frame is mounted the mechanism which receives the noodles from the cutter E and folds them automatically and at high speed. The cutting mechanism may be operated in any suitable way, parts of the gearing are indicated, and as shown the spur-wheel *b* on the shaft of the lower feed roller B meshes with a spur-wheel *e* on the shaft of the rotary cutter E. A pinion *e'* on the same shaft meshes with a spur-wheel *g* on a shaft G which operates the endless chains which convey the tables toward and from the noodle-cutting mechanism. The pinion *e'* may be connected with the shaft E' of the rotary cutter E by means of clutch mechanism E'' of any suitable construction. Preferably the spur-wheel *g* is mounted on the hub *h* of a disk H which is connected with the shaft G by a groove and feather connection *h'* and said disk is connected with the spur-wheel *g* by bolts *h''* in order that by adjusting the position of the spur-wheel *g* relatively to the disk H, the positions of the tables relatively to the cutters may be properly adjusted so that the tables will receive the cut needles at the proper time and in proper positions. The shaft G is mounted in suitable stationary bearings at the inner end of the extension F' of the main frame. At the outer end of this part of the frame there is a shaft I mounted in adjustable bearings I' of well known construction. The shafts G and I carry sprocket-wheels J' that support and operate the sprocket-chains J. The construction as thus far described is such that as the cutters and presser rolls are operated, in the manner before described, the sprocket chains J are moved to convey the folding tables first away from the cutting mechanism and then back to such mechanism in the manner herein-after described.

Between the opposite sides of the extension F' and between the shafts G and I is located a plate L which is attached to the opposite side plates of the part F' of the frame in any suitable way and it is provided with means, hereinbefore described, which operate upon the tables, hereinbefore referred to, to shift them sidewise to give to the noodles a diagonal arrangement on the tables. This plate L also carries devices for operating on other devices which turn some of the tables to give certain folds to the noodles while the devices for operating other tables for a similar purpose are carried by other parts of the frame.

The chains J, hereinbefore referred to, and as shown in Fig. 7, are supported by strips M attached to the frame F' which prevent them from sagging and similar strips M' may be secured to the frame above those portions of the chains located above the plate L. The chains carry at regular distances

apart inwardly projecting arms j which support certain links and levers for operating the noodle-folding tables. These devices will be presently described in detail.

5 As before stated, the tables are divided into sets, there preferably being four tables in each set, although this number may be varied, but I will here assume that each set comprises four tables, that the first, third and fourth table in each set are mounted to turn in such manner as to fold the noodles, while the second table in the set is not so turned but supports the completely folded noodle and delivers it to the endless carriers.

10 Each table in each set is, however, provided with means for shifting it sidewise and this means preferably comprises on each table a bar N which supports the table and which extends through guides n riveted or otherwise secured to the table. Each table also has riveted to it a bracket n' carrying a roller n^2 and the bar N extends through the brackets n , n' loosely so that the table can be moved endwise on the bar without moving the bar laterally. By reference to Fig. 8 it will be observed that the rollers n^2 are disposed diagonally, the rollers on the tables numbers 1 and 2 being on one side of the central line between the chains J and the rollers of the tables 3 and 4 on the opposite side thereof. These rollers coöperate with the lugs O' , O^2 , O^3 and O^4 . These lugs are formed integrally with the plate L , or otherwise connected therewith and are so disposed as to cause the tables 1 and 2 to be shifted toward one side of the mechanism and the table 3 and 4 to be shifted or moved slightly in an opposite direction when the tables are above the plate L . In order to move the tables back to their original position with their ends in line with each other, lugs P' , P^2 , P^3 and P^4 are provided on the under side of the plate L . By this mechanism as the chains J are revolved they carry with them the tables, shift the tables in opposite directions sidewise and then return them to their original position. This operation is shown diagrammatically in Figs. 21 to 24. In Fig. 21 the tables have their ends in line with each other and the noodles X are parallel. Fig. 22 shows how the tables are shifted, numbers 1 and 2 being shifted slightly in one direction and tables 3 and 4 being shifted in the opposite direction, No. 1 being moved to a somewhat greater extent than number 2, and number 4 being moved somewhat more than number 3. This will give the desired diagonal arrangement of the noodles before they are folded. Fig. 23 shows how the noodles are folded after they are inclined and Fig. 24 shows the final operation of folding.

55 The bars N of tables 1, 2, 3 and 4 of each set are connected together by links R' , R^2 , R^3 , R^4 and the bars N of tables 1, 3 and 4

of each set are provided with operating levers S' , S^3 and S^4 for tilting the tables to fold the noodles. The bar N of table No. 2 not being tilted has no corresponding levers. Each bar N is provided with a link R' , R^2 , R^3 or R^4 at each end and each link is formed with a recess r' , r^2 , r^3 or r^4 to receive a bar N . The bar N of table No. 1 has secured to it at each end an operating lever S' . The bars N of the tables 3 and 4 carry corresponding operating levers S^3 , S^4 and these bars, links and levers are assembled in the manner shown in Fig. 8. The links R' , R^3 , R^4 are formed with bosses r^{11} , r^{33} , r^{44} and through these bosses extend certain arms j of the chains J and on these bosses are pivoted the levers S' , S^3 , S^4 . Said levers are held in their normal positions and are returned to their normal positions by coiled springs T' , T^3 , T^4 contained within the bosses r^{11} , r^{33} , r^{44} engaging the levers and held in the manner shown in Figs. 8 and 16. The arrangement is such that the tables may be shifted sidewise in the manner before described without moving the links and levers and in such manner that the tables 1, 3 and 4 may be independently turned to fold the noodles while the series of sets of tables with their operating links and levers are being carried to and from the noodle-cutting mechanism. The bar N of table No. 2 is rigidly secured to the links R^2 by screws r^{10} , see Fig. 13. Each end of the bar of table No. 1 is rigidly secured to its operating lever S' and the bars N of tables Nos. 3 and 4 are similarly secured to their levers S^3 , S^4 .

Referring now to Fig. 8, it will be seen that on each side of the machine the link R' of table No. 1 has its boss r^{11} mounted on an arm j of the chain J , the opposite end of the link being mounted to turn on a sleeve t on the next arm j in advance of the arm first mentioned. The link R^2 of table No. 2 has its front portion arranged to surround the boss r^{11} of table No. 1, being in fact mounted to turn on a hub s^{11} formed on the operating lever S' which surrounds the boss r^{11} . The rear portion of link R^2 surrounds and turns on a hub s^3 on lever S^3 . Link R^3 which carries lever S^3 has its boss r^{33} surrounding an arm j and its rear portion surrounds a boss s^4 on the lever S^4 . Link R^4 has the boss r^{44} arranged at its front end and surrounding an arm j of the chain, while its rear portion surrounds a sleeve t carried by another arm j of the chain. The links and levers are assembled in this way throughout the series of sets of tables and the arrangement is such that the tables may be carried by the chains successively under the noodle-cutting mechanism, first away from such mechanism and then back to it.

In order to attach the opposite ends of the several sets of links I may join them in the

manner shown in Figs. 6 and 16 where, it will be observed that the links R^2 are divided and bolted to the bar N of table No. 2. The levers S' are adapted to swing upwardly and rearwardly while the levers S^3 , S^4 are adapted to swing upwardly and forwardly, the levers S' being turned by lugs U' on the sides of the frame F' and the levers S^3 and S^4 being engaged by arms U^3 , U^4 secured to the plate L , the arrangement being such that as the tables are advanced, the levers are engaged by said lugs and arms to turn the tables at the proper time. In order to break the shock when the levers encounter the lugs U' and the arms U^3 and U^4 , said levers may be provided with cushioning spring u' , u^3 , u^4 . The arrangement is such that the levers S' and S^4 of each set are first engaged by the lugs U' and arms U^4 and the tables 1 and 4 are turned in the manner indicated in Figs. 6 and 18. As the tables advance the tables Nos. 1 and 4 are returned to their normal position by the springs T' , T^4 and then the levers S^3 engage the arms U^3 and table No. 3 is turned in the manner indicated in Fig. 19, and this table is returned to its normal horizontal position as the tables advance. It will be understood that the four tables in each set receive a series of parallel noodles from the cutters and that the noodles lie close together in a horizontal condition as shown in Fig. 17. After the tables have advanced slightly they are shifted in opposite directions, as indicated in Fig. 22, so that the noodles assume a position diagonal to the direction of movement of the carrier chains. When the levers S' and S^4 encounter the lugs U' and arms U^4 the tables 1 and 4 are turned to the position shown in Fig. 18 to give the first folds to the noodle, then as the tables move farther on away from the cutting mechanism, the tables 1 and 4 are returned to their horizontal positions by the springs T' , T^4 and table No. 3 is operated by arm U^3 as indicated in Fig. 19. Immediately after this lever S^3 passes arm U^3 and table No. 3 is returned to its normal horizontal position, leaving the folded noodles on table No. 2 which carries them to the end of the frame F' and delivers them to the carrier belt W which is of ordinary construction and may be operated in any suitable way. It will be understood that there are lugs U' and arms U^3 , U^4 on opposite sides of the machine, as indicated in Fig. 3, in order that the tables may be operated from both ends. It will be also understood that some of the parts which are shown to be formed integrally with other parts may be separately formed and adjusted where necessary.

The operations are entirely automatic, power being taken from any suitable power shaft and the several parts of the mecha-

nism geared together to work in harmony. The lower ends of the noodles depending from the feeding and cutting mechanism are first received by table No. 1 and then as the noodles descend their following portions are successively received by tables 2, 3, and 4 of a set. This set after assuming a horizontal position and arriving at the proper position in the machine are operated in the manner before described to perform the folding operations and then another set of four tables receives noodles and folds them in a similar manner. Any desired number of sets of tables may be included in the folding mechanism which may be indefinitely prolonged, and while I have shown each set of tables as comprising four tables, one of which is stationary and the others movable relatively to the carrier belt, the number may be varied.

I claim as my invention:

1. A machine for making folded noodles, comprising mechanism for cutting a sheet of dough into strips, and folding mechanism consisting of an endless series of sets of tables which receive the noodles from the cutting mechanism, each set of tables being provided with devices for operating the tables to fold the noodles over upon themselves and means for shifting the tables of each set in opposite directions.

2. A machine for making folded noodles, comprising mechanism for cutting a sheet of dough into strips, and folding mechanism consisting of a set of tables which receive the noodles from the cutting mechanism, mechanism for moving the tables toward and away from the cutting mechanism, devices for operating the tables to fold the noodles over upon themselves while they are being carried away from the cutting mechanism and means for shifting the tables transversely to different extents.

3. A machine for making folded noodles, comprising mechanism for cutting a sheet of dough into strips and folding mechanism comprising a set of horizontally arranged folding tables which receive the strips of dough from the cutting mechanism, mechanism for moving the tables successively away from the cutting mechanism, means for operating the two end tables in the set to give the first fold to the noodles, means for operating another table in the set to give the final fold to the noodles, and mechanism for shifting the tables laterally before the noodles are folded.

4. The combination with noodle-cutting mechanism, of a horizontally arranged set of folding tables, mechanism for moving them successively past the cutting mechanism, means for shifting the tables laterally to cause the noodles to assume a position diagonal to the line of movement of the tables, and devices for operating the tables to fold

the noodles over upon themselves as they move away from the cutting mechanism.

5. Noodle-folding mechanism comprising conveyer chains, a set of folding tables carried thereby, means for shifting the tables laterally and mechanism for operating the tables to fold the noodles after they have been shifted.

6. Noodle-folding mechanism comprising 10 a series of sets of four tables, one of which tables in each set maintains a horizontal position during the folding operation, mechanism for operating the first and fourth tables of the set to give the first folds to the 15 noodles and means for operating the third table of the set to give the final fold to the noodles.

7. Noodle-folding mechanism comprising 20 a supporting frame, sprocket chains supported therein, folding tables supported and carried by the sprocket chains, devices on the frame for shifting the tables laterally as they are advanced by the sprocket chains and devices connected with the tables and 25 engaged by said devices on the frame for effecting such lateral movement.

8. Noodle-folding mechanism, comprising 30 a series of four tables, one of which maintains a horizontal position during the folding operation, mechanism for operating the first and fourth tables of the set to give the first folds to the noodles, and means for operating the third table of the set to give the final fold to the noodle while supported by 35 the second table in the series.

9. In a noodle-folding machine, the combination with a supporting frame, noodle-cutting mechanism, a horizontally arranged set of folding tables, mechanism for moving 40 the tables successively to and from the cutting mechanism, devices for operating the tables to fold the noodles over upon themselves as they move from the cutting mechanism, rollers on the tables, and inclined lugs 45 on the frame of the machine engaging said rollers to shift the tables laterally.

10. Noodle-folding mechanism comprising a frame, noodle-folding tables supported by the frame, cross-bars which support the tables and with which they have a sliding 50 connection, means for advancing the tables, means for operating the cross-bars to turn the tables and thus fold the noodles, and devices for shifting the tables laterally on the cross-bars without moving the cross bars 55 endwise.

11. Noodle-folding mechanism comprising a frame, sprocket chains supported thereby, noodle-folding tables, cross-bars on which they are supported, links connected with the 60 cross-bars and pivotally connected with the sprocket chains, means for moving the tables laterally on their supporting bars, levers connected with said bars and means for operating said levers to turn some of the cross 65 bars and tables as they advance.

12. Noodle-folding mechanism comprising a supporting frame, sprocket chains mounted therein, means for operating said chains, noodle-folding tables, cross-bars on which 70 they are mounted, means for moving the tables transversely on the cross-bars, links pivotally connected with the sprocket chains and the cross bars, levers pivotally connected with the sprocket chains and attached to 75 some of the cross-bars, and means carried by the frame and engaging said levers to turn some of the tables during the folding operation.

13. A noodle folding table in combination 80 with a cross-bar on which it is mounted to slide laterally, means for moving the table transversely on the cross bar an operating lever secured to said cross-bar and means for turning the cross bar. 85

In testimony whereof, I have hereunto subscribed my name.

ANTON WILD.
